PARTITION WALL

Adolf Häammerle, Modling, Austria

Application February 13, 1933, Serial No. 656,492
In Austria February 24, 1932

1 Claim. (Cl. 72—116)

It is known to make partition walls by plastering wire netting, plaited wire or similar supporting means on one or both sides with mortar.

The invention consists in that a plurality of 5 polygonal dowel-like bodies made of concrete or the like are loosely inserted in the meshes of the netting after it has been erected for the purpose of holding the mortar. The advantage of the wall according to the invention is that the 10 adhesion between the support and the mortar is increased.

An embodiment of the invention is illustrated by way of example in the accompanying drawing in which:—

15 Fig. 1 shows a portion of the support with an inserted dowel.

Fig. 2 is a section through a portion of a finished wall.

Dowel-like bodies A are inserted in the meshes 20 B of the support of wires D. The dowel A has a steep inclined portion C between its shank and head designed to prevent the dowel from falling out of a mesh of the support.

25 By this construction of the dowel a head is formed at C which is wider than the width of the meshes of the wire netting, so that this head cannot pass through the meshes. The portion of the dowel body A extending from the head C also widens but only to such an extent that it 30 can easily be passed through the meshes of the

wire netting. As this portion is heavier than the head C, the dowel hangs in an inclined position in the netting and cannot drop out. The dowels A are inserted relatively close together in the wire netting after it has been set up in a well known manner, and the mortar is then applied which on both sides of the wire netting adheres to the flat faces of the dowels and does not slide off the same as is the case when round dowels are employed.

The dowels A are not woven in the wire netting D, as in similar old constructions. Consequently the production is cheapened and the material requires less space for transporting because the wire netting can be tightly rolled without the dowels which can be accommodated in a separate container.

I claim:—

A partition, comprising in combination a wire netting, polygonal dowel-like bodies adapted to be inserted in said netting to hold the mortar on said wire netting, each body consisting of a shank of rectangular cross-section widening gradually towards one end and widening at a sharp incline at its other end to form a head, the gradually widening end of the shank being heavier than said head to cause said body to assume an inclined position in the netting.
